UNITED STATES PATENT OFFICE.

WILLIS S. SHAFT, OF FARIBAULT, MINNESOTA.

FILE AND FILE CABINET FOR LETTERS OR OTHER PAPERS.

Application filed September 25, 1920. Serial No. 412,766.

To all whom it may concern:

Be it known that I, WILLIS S. SHAFT, a citizen of the United States, residing at Faribault, in the county of Rice and State of Minnesota, have invented certain new and useful Improvements in Files and File Cabinets for Letters or Other Papers; and I do hereby declare the following to be a full, clear, and exact description of the invention, such as will enable others skilled in the art to which it appertains to make and use the same.

My invention has for its object to provide an improved file and file cabinet for letters or other papers, of the kind which need to be kept readily accessible in offices or elsewhere for convenience of reference in the conduct of business; and, to this end, my invention consists of the novel devices and combinations of devices hereinafter described and defined in the claims.

My invention, in its preferred form, is illustrated in the accompanying drawings, wherein like notations refer to like parts throughout the several views.

In said drawings,

Fig. 1 is a perspective view showing my improved cabinet with several of my improved files supported therein—the others being removed;

Fig. 2 is a vertical section on the line 2—2 of Fig. 1 through a portion of the cabinet and through the whole or portions of some of the files supported therein;

Fig. 3 is a perspective view of one of the files detached, the dotted lines showing the way in which the file is handled by the hand of a person taking hold of the index finger;

Fig. 4 is a view of the mouth portion of one of the files, in section on the line 4—4 of Fig. 3, as the same would appear when laid down flat-wise on a table or other support, the dotted line showing how the index finger of the file is manipulated by the hand of a person to separate the mouth lips and open the file;

Fig. 5 is a view in end elevation showing one of the files as it might appear when laid down flat-wise on a table or other support, this being on a smaller scale than Figs. 2, 3 and 4;

Fig. 6 is a perspective view showing one of the files as it might appear when the pocket is completely opened up so as to

bring its two walls into line with each other and then laid down flat-wise with its interior surface and the contents of the pocket exposed to view; and

Fig. 7 is a perspective view showing the end portion of a file having pocket walls of comparatively stiff material, instead of being made of cloth or tough paper, as in the other views.

The cabinet is shown as made up of an open face box-like body 8 provided with vertical dividing partitions 9 and a series of file-suspending rungs 10 passing through these partitions 9 and having their ends seated in the end walls of the body 8. These rungs are suitably spaced apart from each other in a common vertical plane near the face of the cabinet, so as to leave space between the rungs for the insertion and removal of the files, and space behind the rungs for the suspension of the files.

Each file is composed of a pocket 11, conveniently and preferably formed from a piece of cloth or other flexible material centrally folded and of the proper size for holding the letters 12 or other papers therein, and a pair of lips marked, respectively, 13 and 14, composed of rigid material, preferably thin metal, secured to the end margins of the piece of folded cloth 11. The lip 13 is wider than the lip 14, and has one of its margins folded over one end of the cloth body 11, while its opposite margin is rolled over to provide a bill. An index finger 15 is carried by the lip 14 and is adapted to be engaged with lip 13 through a slot 13^a in the latter, to retain the body in a closed position. Each of the fingers 15 has indicia 15^a thereon to identify the contents of the cloth body or file on which it is mounted. Further, these fingers serve as handles by which the files may be conveniently carried. The bill of the lip 13 affords a means for suspending the closed file within the cabinet, from one of the rungs 10 thereof, as best shown in Fig. 2 of the drawings. The index finger 15 is preferably composed of metal and is so shaped, that, when the lips are closed, it will engage with the walls of the passage 13^a of the lip 13 freely with a hook-like action, and thereby hold the lips in their closed position, and will be readily forced out from the said passage 13^a, when the file is removed from the cabinet and laid

105
110

down flat-wise with its lip 13 resting on a table or other support, as shown in Fig. 4 of the drawing.

The lip 14 is shown as turned inward at 5 its upper edge into a short roll affording a stiffening bead 14^a, which abuts the inner face of the lip 13 when the parts are in their closed position, as shown in Fig. 2. As a matter of convenience for connecting 10 the lips 13 and 14 with the ends of the pocket-forming cloth 11, the lower ends of the said lips are upturned and made to embrace down-turned end folds of the cloth between the same and the bodies of said 15 lips under a clamping action, in a manner which is obvious from Figs. 2 and 4 of the drawings.

The correspondence or other papers 12 are classified with reference to an index, 20 and to the respective files, and each file has its own independent index notation, such as the numeral "1", shown on the papers in Fig. 6 and on the index finger 15 in Fig. 3 of the drawings, and various 25 other numbers such as shown on the index fingers of the files mounted in the cabinet, as illustrated in Fig. 1.

The partitions 9 of the cabinet are so located, in respect to each other and the side 30 walls of the cabinet, that the files fit snugly within the respective compartments of the cabinet formed by these partition walls; and hence, the ends of the file will abut the partitions or end walls, and thereby prevent endwise displacement of the letters or 35 other papers in the files, when the latter are in the cabinet.

In the modification shown in Fig. 7, the 40 pocket is represented as composed of two sections 16 and 17, of comparatively rigid material, pivotally connected at their lower ends by a hinge joint 18. The said sections 16 and 17 may be made of any suitable material, such as stiff cardboard, wood 45 veneering or thin metal, and the hinge joint 18 be of any suitable kind, preferably made out of metal. In other respects, the pocket of this modification, illustrated in Fig. 7, is identical with that shown in the main 50 views, and is intended to be employed in the same way.

The practicability and utility of my improved file and file cabinet has been demonstrated by the successful commercial usage 55 thereof.

It will, of course, be understood that more or less of the details may be changed without departing from the spirit of the invention.

60 What I claim is:—

1. A file for letters or other papers comprising a pocket adapted to hold the papers and which pocket has one lip of hook-shape at its outer margin and provided with a passage for an index finger and which pocket

has on its other lip an index finger adapted to project through said passage when the lips are in their file-closing position, and which hook-shaped lip affords means for suspending the closed file in a supporting 70 cabinet with the index finger in sight, substantially as described.

2. A file for letters or other papers comprising an expansible pocket adapted to hold the papers and which pocket has one 75 lip of hook-shape at its outer margin and provided with a passage for an index finger and which pocket has on its other lip an index finger adapted to project through said passage, when the lips are in their 80 file-closing position, and which hook-shaped lip affords means for suspending the closed file in a supporting cabinet with the index finger in sight, substantially as described.

3. A file for letters or other papers comprising a flat pocket having its body portions composed of flexible material and its lip portions composed of rigid material, one of said rigid lips being hook-shaped at 90 its outer margin and provided with a passage for an index finger and the other of which rigid lips has an index finger adapted to project through said passage in the hook-shaped lip, when the lips are in their file-closing position, and which hook-shaped lip 95 affords a means for suspending the closed file in the supporting cabinet with the index finger in sight, substantially as described.

4. The combination with an open face cabinet having vertically spaced and aligned 100 supporting means, of files comprising folded sheets, having a lip extending transversely along one end thereof, said lip being curved to form a hook adapted to face inwardly of 105 said cabinet and co-operating with said supporting means whereby the files are suspended in said cabinet in overlapping relation with the said lips concealed between said supporting means, and means on said files projecting forwardly of said lips for 110 lifting and withdrawing the same.

5. A file for letters including a sheet 115 adapted to receive correspondence and foldable to incase the latter, said sheet having means secured to one end thereof having a curved edge adapted to pendently support the file, and an index finger secured to the opposite end of the file, said means having an opening therein through which said index finger passes to hold the file in closed 120 position, said finger also forming means by which the file may be carried.

6. The combination with an open face cabinet having a plurality of file-suspending 125 rungs vertically spaced apart from each other, of a plurality of files, each provided with a hook-ended lip adapted to suspend the file from one of said rungs, and having a passage for an index finger and each file having another lip provided with an in- 130

dex finger working through the said passage of the hook-shaped lip and bearing an exposed index notation, substantially as described.

5. 7. The combination with files having open ended pockets for holding letters or other papers, of a cabinet having one or more compartments for receiving said pockets with the vertical walls of the compartments spaced apart so as to snugly abut the open ends of the files, when the latter are in the cabinet, vertically spaced horizontal rungs near the front edge of said compartments, and means extending across 10 one end of the files for engaging over said rungs to suspend the files therefrom.

8. A file for letters comprising, a flexible sheet adapted to be folded intermediate its ends to form a letter-holding pocket, 15 stiffening strips at each end of said sheet,

one of which has its outer edge formed as a curved bill adapted to hook over a rod to pendently support said file, said strips contacting when the sheet is in folded position, and including means for holding the 25 sheet in closed position.

9. A letter file with flexible body, supported by one of its ends, and having its opposite end folded over a line intermediate of said body to provide a pocket for the reception of letters, and means to prevent casual opening of the pocket, said means being provided with indicia to identify the 30 contents of said pocket.

In testimony whereof I affix my signature 35 in presence of two witnesses.

WILLIS S. SHAFT.
